UNITED STATES PATENT OFFICE.

SAMUEL J. MILES, OF CHICAGO, ILLINOIS, ASSIGNOR TO FERDINAND SIEGEL,
OF SAME PLACE.

FURNACE.

SPECIFICATION forming part of Letters Patent No. 468,814, dated February 16, 1892.

Application filed October 28, 1889. Serial No. 328,389. (No model.)

To all whom it may concern:

Be it known that I, SAMUEL J. MILES, residing at Chicago, in the county of Cook and State of Illinois, have invented a new and useful Improvement in Furnaces, of which the following is a specification.

My invention relates to furnaces, and particularly such as are adapted to be used for the purpose of burning slack and the like, and has for its object to provide convenient means for this purpose.

My invention is illustrated in the accompanying drawings, wherein—

Figure 1 is a cross-section of the fire-box, showing my appliances in position. Fig. 2 is a transverse section of the same view, parts in section and parts broken away. Fig. 3 is a view of the air-pipes. Fig. 4 is a cross-section of one of the grate-bars; Fig. 5, a cross-section of grate-bar cover; Fig. 6, a plan view of the same.

Like parts are indicated by the same letters in all the figures.

A is the boiler, suitably supported; B, the fire-box; C, the ash-pit, and D D the surrounding walls.

E is a fan, from which leads the pipe E', having the branches E² E², which terminate, respectively, in the distributing-tubes E³ E³, from each end of each of which rises a pipe E⁴. These pipes are connected above by the cross-pipes E⁵ E⁵.

F F are perforated pipes passing longitudinally through the V-shaped grate-bars G and resting on the cross-bridges H H in the same. Each pipe F F opens at its extremities into the pipes E⁵ E⁵, as indicated in Fig. 1. The cross-bridges H H divide the grate-bars G into compartments, as indicated, and from each of these compartments opens downwardly a perforated nipple J. Each of these nipples has a transverse slot, through which reciprocates the slide K. This slide is provided with a series of apertures L L, which can be made to register with or intercept the apertures in the nipples J J. Each grate-bar G is provided with a cover M, and this cover is provided with a number of longitudinal slots N N and a series of cross-grooves O. The grate-bars G terminate at the extremities in

the curved portions P P, adapted to receive the transverse pipes E⁵ E⁵ and perforated to permit the passage of the pipe F therethrough.

R is the passage-way leading to the ash-pit, and S the passage-way leading to the fire-box. 55 These parts might be greatly changed without departing from the spirit of my invention.

The use and operation of my invention are as follows: A quantity of coal-slack, preferably hard-coal slack, being placed upon the grate-bars G or in the fire-box B and the passages at the apertures R and S being preferably 60 closed, a suitable blast of air is driven by the

fan E through the pipe E' and pipes E² into pipes E³ E³, whence it passes through the upwardly-turned pipes E⁴ E⁴ into the transverse pipes E⁵ E⁵. From these latter it passes in both directions into the pipes F F in the grate-bars G, whence it is expelled through the apertures in such pipe and through the 70 slots N N in the covers M of the grate-bars. This secures the even and regular distribution of the air. The arrangement of the parts

is also such that the ash-pit is always clear, thus permitting free access to the working 75 parts of the furnace. When the grate-bars G become clogged, they can be cleaned by moving the slide K until its apertures L reg-

ister with the apertures of the nipples J, whereupon the blast of air will discharge the 80 contents of each section or compartment of the grate-bar through its nipple J into the ash-pit. The various pipe connections can

be made in any desired and convenient manner and by any suitable couplings, nipples, 85 and connections such as are commonly used for similar purposes. The grate-bar lids M are made so as to fit between the sides of the bars, so that the grate presents a practically uniform surface with occasional slots. These 90 slots are greatly enlarged for the purposes of illustration. Apertures of any kind could be substituted for them. The groove is adapted to permit the easy breaking of these lids into sections, so as to permit the easy removal and 95 introduction and permit injured portions to be removed and replaced.

Having thus described my invention, what I claim and desire is as follows:

1. The combination of hollow grate-bars 100

with apertures therein, supply-pipes connected therewith and leading thereto through the corners of the ash-pit, and a fan which forces air into such supply-pipes.

5. 2. In a furnace, the combination of a series of V-shaped grate-bars with perforated supply-pipes passing therethrough and perforated lids thereon.

10. 3. In a furnace, the combination of a series of grate-bars with supply-pipes passing therethrough and cross-bridges therein on which such pipes rest.

4. In a furnace, the combination of an open spaced fire-box, an ash-pit with hollow grate-

15. bars, an underground supply system of pipes and connections between such system, and

grate-bars passing through the corners of the ash-pit, so as not to obstruct the same.

5. In a furnace, the combination of a series of grate-bars, each having a series of downwardly-depending perforated slotted nipples, and a series of perforated slides adapted to reciprocate through the slots in the nipples of each grate-bar.

6. In a furnace, upwardly-open grate-bars 25 provided with a perforated lid therefor, the same transversely slotted to permit of an easy breaking into sections.

SAMUEL J. MILES.
